PENCIL SHARPENER

Ivan Georg André Ljunggren, Stockholm, Sweden,

Application December 21, 1946, Serial No. 717,688
In Sweden October 30, 1944

2 Claims. (Cl. 120—96)

1

In the sharpening of pencils in pencil sharpeners, a certain cautiousness must be observed to avoid the breaking of the point of the pencil during continued operation upon the same after the sharpening of the lead has been completed. Therefore the sharpening of the pencil will take a longer time than would otherwise be necessary, without the risk of the breaking of the ready-sharpened point being entirely eliminated. The present invention has for its object to obviate this disadvantage, and principally consists in that the pencil sharpener is provided with a signalling means activated by the influence of the pencil or the point thereof, when the latter comes into the position in which the sharpening of the pencil is completed. The signalling means may be of any suitable kind, for instance of the type giving an acoustic signal. Preferably, however, acoustic signalling means is used in the form of a bell, the signalling mechanism of which is activated or triggered in a certain position of the pencil or the point thereof, the arrangement being preferably such that the signalling mechanism is actuated from the driving means of the machine to give a signal.

The invention will be described more closely with reference to the accompanying drawing, which illustrates a manually operable pencil sharpener provided with a signalling means according to the invention. Fig. 1 is a cross section through the machine, and Fig. 2 shows a section through the portion of the machine on which the bell and the appertaining actuating device are arranged. Fig. 3 is a section on line 3—3 in Fig. 1.

The operating members of the machine are enclosed in a two-part hood, the one part 1 of which, being of a substantially conical shape, forms the machine frame and is provided with a base 2 for the securing of the machine to a substructure or a wall, and the other part 3 of which forms a cover consisting preferably of some transparent artificial resin or the like, said cover being formed into a shaving box 4 to collect the shavings formed in the sharpening operation, as well as into a sleeve-shaped holder 5 for the pencil 6. Part 3 is connected to part 1 by means of a bayonet coupling comprising pins 7, 8 arranged on part 3 and slots provided in part 1 and adapted to be engaged by the pins 7, 8. To facilitate the arrangement of the machine on a horizontal substructure as well as on a vertical wall, in a manner such that the shavings may be collected in the shaving box 4 in both positions of the machine, two pairs of a bayonet slot are preferably

provided in part 2 in positions angularly displaced by 90°, so that part 3 may be angularly adjusted relatively to part 1 in a corresponding manner. To facilitate this shifting of part 3, without altering the location of the pencil relatively to the knife, parts 1 and 3 are united with each other through cylindrical portions 9 and 10 coaxial with the axis of the pencil or pencil holder.

The rotating sharpening member consists of an irregularly shaped body 11 provided with a conical recess 12 for the pencil point 13 opposite the pencil holder 5, said recess being provided at 14 with an incision extending along a generatrix, beside which incision the knife 15 is arranged in such manner as to be permitted to operate upon the pencil point along the portion thereof accessible through the incision. The knife 15, which consists of a plane rim of teeth formed as a cutter, is secured on a shaft 16 rotatably mounted in a holder 17, which is removably connected with the sharpening member 11 by means of screws 18. The sharpening member 11 is rigidly connected with a driving shaft 19 mounted in part 1, said driving shaft permitting of being rotated by means of a manually operable crank 20. At the opposite end, the sharpening member 11 is rotatably mounted on the pencil holder 5, which is for this purpose provided with a metallic bearing sleeve 21. The driving shaft 19 and the pencil holder 5 are thus coaxially arranged. To attain the requisite balance in the rotating system, the sharpening member 11 is provided with a counterweight 22 adapted to balance the weight of the knife holder 17 and the parts mounted thereon.

The knife 15 is adapted to be driven from the shaft 19 by means of a planet gearing comprising a bevel gear 23 rigidly secured on the knife shaft 16, and a plane rim of teeth 24 rigidly secured in part 1 and adapted to engage the gear wheel 23. When the crank 20 is rotated, the sharpening member 11 with the knife holder 17 and the parts mounted therein will rotate with the driving shaft 19, the gear wheel 23 being thus caused to roll on the toothed rim 24. Consequently, the knife holder 17 will perform a rotary motion about the pencil, while the knife is simultaneously caused to rotate in the holder. If the pencil 6 is then retained in the holder, the point of the pencil will be operated upon by the knife 15 about the whole circumference of the pencil, so that a conical shape will be imparted to the pencil point in correspondence to the recess 12.

The signalling means consists of a bell 25 and a clapper 26. The bell 25 is secured in the frame

1 coaxially with the driving shaft 19. The clapper 26 is constituted by a portion of a resilient piece of sheet-metal 27, which is riveted to the bent end portion 28 of a resilient tongue 29, which is swingably connected by means of a screw 30 to an arm 31 projecting from the counterweight 22 in such manner as to permit of being swung in a plane parallelling the knife 15. Otherwise, the tongue 29 is so arranged as to be actuated by the pencil point 13, when the pencil comes into the position in which the sharpening of the lead 32 is entirely or approximately completed. The tongue 29 will thus be swung about the screw 30 through the influence of the pencil point against the action of a spring 33, through which the signalling mechanism is normally kept in inoperative position. When the tongue 29 is actuated by the pencil point in the manner set forth, the signalling mechanism is brought into the position indicated by chain-dotted lines in Fig. 2, an arm 34 bent outwardly from the piece of sheet-metal 27 being thus brought into a position such that the outer end thereof will, upon continued rotation of the shaft of the pencil sharpener, hit the heads of a number of securing screws 35, which in the example shown are four in number, and by means of which the toothed rim 24 is secured in the frame 1. When the arm 34 strikes against said screw heads, a swinging movement is imparted to the clapper 26, the bell 25 being thus actuated to give a signal, which indicates that the sharpening of the pencil is finished.

Obviously, the construction and the arrangement of the signalling means may be modified in various ways. Thus the signalling mechanism may be arranged to be operated by a spring, which is normally locked, and which is triggered by the point of the pencil, the tensioning of the spring being then effected by the driving means of the machine, for example.

What I claim is:

1. In a signal device for a pencil sharpener

having a rotary sharpening element and a housing therefor, in combination, a bell mounted on the housing coaxially with the sharpening element, signal operating means pivotally mounted on the sharpening element and extending across the path of the pencil point as it is fed during sharpening, a clapper resiliently mounted on said operating means, said clapper having an extension thereon adapted to make contact with stationary portions of the housing when said signal operating means is pivoted to cause said clapper to oscillate in a direction perpendicular to the feeding movement of the pencil and resilient means for holding said signal operating means in its inoperated position.

2. In a signal device for a pencil sharpener having a rotary sharpening element and a housing therefor, in combination a bell mounted on the housing coaxially with the sharpening element, a signal operating means pivotally mounted on the sharpening element and extending across the path of the pencil point as it is fed during sharpening, means for resiliently holding said operating member in unoperated position, a resilient clapper mounted on the end of said operating means opposite the pivot point, said clapper extending perpendicularly to said operating means and an extension on said clapper extending outwardly therefrom and adapted to make contact with stationary portions of the housing to cause said clapper to oscillate in a direction perpendicular to the feeding movement of the pencil to thereby ring said bell without reacting upon the sharpened pencil.
